ENOCH OHNSTRAND, OF KENMORE, NEW YORK, ASSIGNOR TO REMINGTON RAND INC.,
OF NEW YORK, N. Y.

DESK DRAWER LOCK

Application filed November 15, 1927. Serial No. 233,431.

This invention relates to improvements in locking devices for desks, and particularly to desks having a series of pedestal drawers and a center drawer.

It is an object of the invention to provide a locking mechanism for desk drawers which may be conveniently mounted on the front wall of the center drawer and operated when the drawer is closed to lock the same in closed position, which is also adapted to operate a suitable independent locking means for the pedestal drawers.

Another object of the invention is to provide a locking mechanism of substantially unit form which may be readily mounted on the front wall of the center drawer of a desk, which is simple in construction, and provided with a locking member adapted to engage the desk in locking position, which is also adapted to operate a suitable locking means for the pedestal drawers.

A still further object of the invention resides in providing a locking mechanism for the center drawer of a desk having a locking cam operable for cooperation with the desk in locking the center drawer in closed position, while a suitable locking means for the pedestal drawers includes a rocker member mounted in the desk for engagement with the locking cam for movement thereby to set the locking means for the pedestal drawers in position to lock these drawers in closed position.

Another feature of the invention resides in providing a locking unit for the center drawer of a desk having a suitable operating handle for the locking cam constructed to detachably receive a key operated locking mechanism adapted to lock the handle against movement when the cam is in drawer locking position, and through the medium of the cam serves to control the position of a locking means for the pedestal drawers.

The invention includes numerous other objects which reside in the specific construc-

tion and association of parts more particularly pointed out in the following detailed description and claims directed to the preferred form of the invention, it being understood, however, that various changes may be made in the relation between the parts which are within the scope of the invention as herein set forth.

In the drawings forming part of this application,

Fig. 1 is a vertical transverse section through the central portion of a metal desk showing the improved locking device applied in the center drawer, portions being broken away for convenience in illustration, the parts being shown in locked position.

Fig. 2 is a view similar to Fig. 1 with portions omitted and illustrating the relation of the parts in the unlocked position.

Fig. 3 is a horizontal sectional view taken substantially on the line 3-3 of Fig. 2 and illustrating only one end portion of the center drawer in its associated relation with the adjacent desk structure and a portion of an adjacent pedestal drawer.

Fig. 4 is a horizontal sectional view through the locking mechanism mounted in the front wall of the center drawer taken substantially on line 4-4 of Fig. 1.

Fig. 5 is a front elevation of the center drawer showing the portions illustrated in Fig. 4.

Fig. 6 is a view similar to Fig. 4 of a slightly different form of locking mechanism.

Fig. 7 is a front elevation of the construction shown in Fig. 6 as applied to the front of the center drawer.

Fig. 8 is a transverse section through the lock and handle member shown in Fig. 4 showing how the lock and handle are secured together.

The locking mechanism of this invention is designed more particularly for application to flat top office desks as shown in Figs. 1 to 3 inclusive, in which the desk includes a

top section 1, and post sections 2 to which are secured panels or side members 3 adapted to form a rigid frame structure. The desk, as usual, is provided with pedestals at one or both ends thereof in which are mounted a plurality of pedestal drawers 4 in the usual manner. The desk is also provided with the usual center drawer 5 which is mounted immediately beneath the top section 1 as clearly shown in Figs. 1 and 2 and which, as usual, extends throughout the central portion of the desk.

Suitable channel members 6 are secured to the panels 3 adjacent the front portion of the pedestal sections of the desk and slidably receive vertically movable locking bars 7. Brackets 8 are secured to these locking bars adjacent each pedestal drawer and extend laterally from one side of the bar. On the ends of the brackets 8 are pivotally mounted the locking pawls 9 as shown in Fig. 1 having shoulder portions 10 for engagement with keepers 11 mounted on the sides of the pedestal drawers 4. These locking pawls 9 have curved extensions 12 extending through openings in the brackets 8 on which is mounted a coil spring 13 normally expansible for retaining the pawls 9 in position to engage the keepers 11 in the manner as illustrated in Fig. 1. The ends of the pawls 9 are rounded as indicated at 14 so that the keepers 11 may engage the rounded end and move the pawls downwardly in the event that the mechanism is moved to the locking position when the pedestal drawers are open. In the closing movement of the drawers the pawls will be depressed to compress the springs 13 and permit the keepers to ride into the locking position shown in Fig. 1 following which the springs 13 will return the latches so as to lock the drawers in closed position. When the pedestal drawers are to be unlocked the bars 7 are moved downwardly so that the pawls 9 are moved below and out of engagement with the keepers 11.

For operating the bars 7 and controlling the locking of the pedestal drawers, there is provided a bell crank lever 15 pivoted to the desk frame as indicated at 16. One end of this lever 15 is pivotally connected at 17 to the upper end of the bar 7 the opening for the pivot pin in the bar being slightly enlarged to compensate for the movement thereof relative to the lever, while the opposite end of this lever is formed with a lateral extension 18 of inverted V-shaped section extending under the center drawer of the desk as shown in Figs. 1 and 2. This lateral extension 18 under the central portion of the center drawer is provided with a plate member 19 for a purpose which will be hereafter described. In a desk having pedestals at opposite ends the locking means for the pedestal drawers as described above will be dupli-

cated in each pedestal and the extension 18 will extend between the bell crank levers.

The center drawer is provided with the usual front wall 20 formed with an opening in the central portion rotatably receiving the handle member 21. This handle member has a flange 22 engaging the front face of the drawer and holding the member in the proper operative position. A lateral extension 23 forms a handle portion by which the member may be manually rotated to operate the locking mechanism. As shown in Figs. 4 and 5 this handle member is tubular in form and receives a locking cylinder 24, a suitable form of key operated cylinder lock, which controls and operates the locking bolt 25.

A supporting plate 26 has a central portion 27 formed with a substantially semi-cylindrical opening 28 in the lower portion thereof of which permits the application of the plate member over the handle member as shown in Figs. 4 and 5. The portion 27 of the supporting plate at one side of the opening 28 is formed with a recess 29 to receive the locking bolt 25 when the handle member is in drawer locking position so that it may be effectually locked against rotation to prevent the opening of the drawer except through the withdrawal of the locking bolt by the operation of the lock with a key. Offset portions 30 are connected to the ends of the central portion 27 and form part of the supporting plate. These offset portions are secured to the front wall 20 of the drawer as shown in Fig. 4 and are provided with lateral extensions 31 having terminal portions to which a retaining plate 32 is secured. The locking cylinder 24 at the rear end portion is provided with a flange 24' which engages against the rear end of the handle member 21.

A locking member or cam 33 having a peripheral flange is secured to the flange portion 24' of the locking cylinder by screws or the like 33', and is formed with a central opening in which one end of the retaining pin 34 is riveted. The opposite end of this retaining pin extends through an opening in the retaining plate 32 and receives the holding pin 35 in a transversely extending opening formed therein. This pin 35 engages the back side of the retaining plate 32 and retains the locking cylinder, handle member and locking cam in proper operative assembly in the desk drawer. The flange on the locking cam 33 terminates in close proximity with the front face of the retaining plate so that endwise movement of the handle member and the locking mechanism will be prevented. This retaining plate 32 is provided with an angle plate 32' which is adapted for cooperation with the locking cam to limit the rotative movement thereof by cooperation with the shoulder 33' shown in Fig. 5. When the shoulder 33' is engaged with the

angle plate 32' the parts will be in the unlocked position at which time the drawer may be opened. The handle member 21 is retained in set position and assembled relation on the locking cylinder which it receives, by the set screw 21' as shown in Fig. 8.

The locking member is formed with a projecting portion at 36 which is adapted to extend through a slot 37 in the bottom of the drawer 5 in the locked position of the parts so it will engage behind the flange 38 for locking cooperation therewith in locking the center drawer in closed position. This flange 38 forms part of the U-shaped member 39 which extends between the opposite ends of the desk under the center drawer and forms part of the frame structure of the desk. When the projecting portion 36 of the locking cam is moved into locking position as shown in Fig. 1 it engages the plate 19 carried by the operating member 18 and moves the plate downwardly to rock the bell crank lever 15 on its pivot and raise the locking bars 7 so that the pawls 9 are moved into position to lock the pedestal drawers in closed position. When the parts are in this position the locking bolt 25 may be projected into the recess 29 in the central portion 27 of the supporting plate to prevent manual operation of the handle member 21. When the locking cam is in center drawer locking position as shown in Fig. 1, the projection 36 holds the plate 19 and extension 18 of the pedestal drawer locking means depressed so that the pawls will lock the pedestal drawer in closed position. When the locking cam is moved to the unlocked position the locking bars 7 will move downwardly by the action of gravity and rock the bell crank lever 15 raising the extension 18 and plate 19 into the position shown in Fig. 2 which will permit opening of the pedestal drawers.

In the construction shown in Figs. 6 and 7 the locking cam 40 is mounted on the shaft extension 41 of the handle member 42, the shaft having bearing contact with the front wall 43 of the drawer and the central portion 44 of a supporting or bearing plate. This supporting or bearing plate is provided with an offset portion 45 parallel and spaced from the front 43 of the drawer at one side of the locking cam 40 which receives one end of the locking cylinder 46. The other end of the locking cylinder is mounted in an opening in the front of the drawer so that the key may be inserted into the cylinder for operating the locking bolt 47 which has locking cooperation in one position with the locking cam 40 through engagement in the recess 48 therein as shown in Fig. 7. The handle member is provided with a suitable handle extension 49 by which the shaft extension 41 and the locking cam may be rotated. The bearing plate is formed with an extension 50 on the end of the offset portion 45 which is

secured to the front wall 43 of the drawer while a lateral extension from the opposite end of the central portion 44 terminates in the offset portion 51 also secured to the front wall of the drawer. The free end of this portion 51 is provided with an extension 52 projecting laterally from the front wall 43 of the drawer for supporting the retaining plate 53 at one end, the opposite end being secured to the block 54 of the locking cylinder. The locking cam 40 is secured on the shaft 41 by the nut 55 which retains the handle member in assembled relation and with the bearing plate prevents detachment of the handle member from the drawer. A projection 56 on the cam member 40 is adapted to engage the block 54 for limiting the rotation of the handle member in one direction. The cam is also formed with a projecting portion 57 which extends through a slot in the drawer for engaging and operating the plate member 19 and locking the center drawer in closed position the same as the construction described in Figs. 1 and 5.

From the above description it should be understood that a locking mechanism is provided for the center drawer which comprises a unit assembled on the front wall of the drawer having a locking member operated into locking and unlocking positions through the operation of the handle member, and having a lock for locking the handle lever against movement in drawer locking position, which locking member controls and operates an independent locking means in the desk in the locked position thereof for locking the pedestal drawers. From this construction the control of all the drawers and the locking thereof is substantially simplified through the special relation of the parts described.

What is claimed is:

1. In a desk drawer lock, the combination with a desk having a plurality of drawers arranged in a pedestal, and a center drawer adjacent said pedestal, of a locking bar mounted in said pedestal for vertical sliding movement, cooperating means on said pedestal drawers and said locking bar adapted for locking engagement in one position of said bar to lock said pedestal drawers in closed position, an operating member for said locking bar extending under said center drawer, a locking member movably mounted in the center drawer, manually operable means connected to said locking member, and a lock mechanism for retaining said locking member in drawer locking position, said locking member being formed for engagement with a portion of the desk for locking the center drawer, and having a projection for moving said operating member and locking bar into locking position.

2. In a desk drawer lock, the combination with a desk having a plurality of pedestal drawers and a center drawer, of a locking

mechanism for said drawers, comprising a shaft rotatably mounted in the front wall of the center drawer, a handle on the shaft in front of the drawer, a locking cam on the 5 shaft inside of the drawer formed to project through an opening in the bottom of said drawer for locking cooperation with the desk, a locking mechanism for retaining said locking cam in locked position, and locking means 10 for said pedestal drawers having an operating member beneath the center drawer adapted to be engaged and actuated by said locking cam for locking said pedestal drawers.

3. In a desk drawer lock, the combination 15 with a desk having a plurality of pedestal drawers and a center drawer, of a manually operable locking member in the center drawer, key controlled means for locking said member in center drawer locking position, 20 and an independent locking mechanism for the pedestal drawers having a part operated by said locking member to move said mechanism into drawer locking position.

4. In a desk drawer lock, the combination 25 with a desk having a plurality of pedestal drawers and a center drawer, of a manually rotatable locking cam mounted in the center drawer and operable in one position to lock said center drawer in closed position, and independent locking means for said pedestal drawers having a part positioned for engagement with said locking cam in locking position, to move said independent locking means into locking position.

35 5. In a desk drawer lock, the combination with a desk having a plurality of pedestal drawers and a center drawer, of a locking mechanism for the center drawer, comprising a handle member rotatably mounted in the 40 front wall of said center drawer, a cam member mounted on said handle formed for locking engagement with the desk, means cooperating with the cam member to limit rotation of the handle member, and independent locking means for the pedestal drawers operated by said cam member.

6. In a desk drawer lock, the combination 55 with a desk having a plurality of pedestal drawers and a center drawer, of a locking mechanism for the center drawer, comprising a handle member rotatably mounted in the front wall of said center drawer, a locking mechanism having key controlled means for locking said handle in one position, a cam member mounted on said handle formed for locking cooperation with the desk in the locked position of the handle, and independent locking means for the pedestal drawers operated by said cam member.

60 7. In a desk drawer lock, the combination 65 with a desk having a plurality of pedestal drawers and a center drawer, of a locking mechanism for the center drawer, comprising a handle member rotatably mounted in the front wall of said center drawer, a key op-

erated locking mechanism carried by said handle member and adapted to lock said handle member in one position against rotation, a cam member mounted on said handle member formed for locking engagement with the desk in the locked position of said handle member, and independent locking means for the pedestal drawers adapted to lock said drawers in the operation thereof by said cam member.

8. In a desk drawer lock, the combination 75 with a desk having a plurality of pedestal drawers and a center drawer, of a locking mechanism for the center drawer, comprising a supporting plate mounted on the inside of the front wall of said center drawer, a handle member rotatably mounted in said front wall and an element on said supporting plate, means carried by the handle member for locking said member against rotation relative 80 to the supporting plate in one position, a cam member mounted on said handle member having a portion adapted for locking cooperation with the desk in the locked position of the handle member, and independent locking 85 means for the pedestal drawers operated by said cam member in locking position, to lock said pedestal drawers.

9. In a desk drawer lock, the combination 90 with a desk having a plurality of pedestal drawers and a center drawer, of a locking mechanism for the center drawer, comprising a handle member having a tubular hub rotatably mounted in the front wall of said center drawer, a locking mechanism mounted 95 in said hub having a part adapted for locking cooperation with a portion of the drawer to lock said handle in one position, a locking cam mounted on said hub having a projection formed for locking cooperation with the 100 desk to lock the center drawer in closed position when said handle member is in locked position, and independent locking means for the pedestal drawers operated by said cam member in the locked position.

10. In a desk drawer lock, the combination 105 with a desk having a plurality of pedestal drawers and a center drawer, of a locking mechanism for the center drawer, comprising a supporting plate mounted on the 110 inside of the front wall of said center drawer, a handle member having a cylindrical hub portion journaled for rotation in the front wall and a part on said supporting plate, a key operated lock mounted in said hub portion having a part for locking cooperation 115 with said supporting plate in one position of the handle member, means for retaining said locking mechanism and said handle member 120 in assembled relation in the front wall of said drawer, a locking cam carried by the handle member and formed for locking cooperation with the desk in the locked position of the handle member, and independent 125

locking means for the pedestal drawers operated by said cam member.

11. In a desk drawer lock, the combination with a desk having a plurality of pedestal drawers and a center drawer, of a locking mechanism mounted in the center drawer having a locking member adapted for locking cooperation with the desk to lock said center drawer in closed position, and an independent locking means for the pedestal drawers mounted in the pedestal having a bell crank lever for operating said means formed with a laterally extending end portion lying in the path of movement of said locking member and adapted for operation thereby to move said locking means into position for locking said pedestal drawers.
